BENDING AND STRAIGHTENING MACHINE

William Rodder, Youngstown, Ohio, assignor to
The Aetna-Standard Engineering Company,
Youngstown, Ohio, a corporation of Ohio

Application April 10, 1946, Serial No. 661,091

10 Claims. (Cl. 153—54)

1

This invention relates to a machine for shaping metal plates by the bending action of a plurality of cooperating rolls. In particular it relates to a machine in which the rolls may be used alternatively either to straighten or to bend a metal plate to a desired contour.

Bending machines and straightening machines that perform their function by passing a plate through cooperating rolls are individually known in the art. The former employ at least three rolls with their axes triangularly spaced apart, and so positioned that a plate will be bent to the desired radius of curvature when fed through the two roll bites formed by a common roll and the other two rolls. Straightening rolls on the other hand act first to bend a metal plate in one direction and then to impart a definite reverse curve to the plate to give it a final shape that is substantially planar. Machines for these uses are necessarily large and expensive, particularly when designed to handle relatively heavy plates; and they require considerable floor space in a fabricating shop. A single machine adapted for use both as a bending and straightening machine would permit a marked reduction in capital investment and in the amount of floor space needed for equipment with which to perform both operations.

It is a general object of the present invention to provide a machine that may be used alternatively either to straighten or bend metal plates. A further object of the invention is to provide a machine in which the majority of the components are used during both plate bending and straightening and a minimum of change over is required to shift the machine from one to the other operation. Another object of the invention is to provide a machine in which three rolls are used for plate bending and are supplemented by a fourth roll for plate straightening. A further object is to support the fourth or straightening roll shiftably for movement to predetermined positions with respect to the bending rolls. Still an additional object of the invention is to provide a drive mechanism for positively driving all of the rolls in the machine. Other objects and advantages of the invention will become apparent from the following specification when considered with the attached drawings. The novel features of the invention are summarized in the claims.

Referring now to the drawings: Figure 1 is a side elevation of a preferred form of the combination bending and straightening machine that forms the subject matter of this invention; Figure 2 is an end elevation of the machine of Figure 55

2

1; Figure 3 is a plan view of the machine of Figure 1; Figure 4 is a schematic section normal to the rolls showing them in position for plate bending; Figure 5 is a schematic section similar to Figure 4, but showing the rolls in position for plate straightening; Figure 6 is a section at the outboard end of the machine through Figure 1 as indicated by the lines 6—6 thereon; Figure 7 is a section, also at the outboard end of the machine, through Figure 6 as indicated by the lines 7—7 thereon; Figure 8 is a broken side elevation, partly in section, of the fourth roll and its supporting and elevating mechanism; Figure 9 is a fragmentary section as indicated by the lines 9—9 of Figure 1 showing a support for the inboard end of the top bending roll; Figure 10 is a detail showing the separable drive for the fourth roll; and Figures 11 and 12 are fragmentary details showing the outboard top roll bearing in its roll supporting and withdrawn positions respectively.

In general the machine of the present invention comprises four rolls, three of which are used for both bending and straightening operations. 25 The fourth roll is used for plate straightening. The group of three rolls is so mounted that one roll is above and approximately midway horizontally between the other two rolls which are beneath it. The top roll forms a roll bite with each of the lower rolls. Due to the fact that the surface of the top roll may be adjusted vertically with respect to a line tangent to the top surface of both the lower rolls a curve of desired radius 30 may be formed in a plate that is passed through the two roll bites.

When the machine is used as a plate straightening machine of the type having two cooperating pairs of rolls the fourth roll is so positioned that it provides a roll bite with the lower roll 40 closest to it and the other lower roll forms a roll bite with the roll of the original group of three immediately above it. As a result a plate may be effectively straightened by a conventional double bending operation as it is passed between 45 the two roll bites formed by these four rolls. All of the rolls are individually driven although the fourth roll is so connected to its drive shaft that it may be disconnected and moved out of the way when it is inoperative.

50 Referring now to Figures 1, 2 and 3 of the drawings the machine there illustrated represents the preferred form of the present invention. It will be understood that the invention is not limited to this disclosure which is for purposes of illustration only. The invention is to be

limited only by the language of the claims. The machine includes a bed 30 that comprises two sections designated at 30a and 30b respectively. They are secured to a foundation by suitable bolts 32 and bolted together at 34. The bed section 30a is formed of a pair of H-beams positioned to provide longitudinal stringers 36 and 37 secured together by H-beam cross members 38 and end plates 39. The entire assembly is preferably welded together but if desired may be bolted or riveted in a manner known in the art. The bed section 30b that is bolted to the bed section 30a comprises a pair of longitudinal H-beam stringers as indicated at 40 and secured together by end plates 42 and 43. The bolts at 34 join the end plates 39 and 43 respectively. Two lift hooks 45 are provided on each side of each of the bed portions 30a and 30b to permit the beds and the equipment mounted thereon to be lifted and moved.

The main drive mechanism is mounted on the bed 30b and includes a main electric drive motor and the necessary gearing leading to the four drive shafts that individually drive the four rolls. This main drive motor is indicated at 50 (Figure 3) and through a coupling 52 drives a worm mounted in a housing 55. A worm wheel driven by the worm is mounted on a shaft that extends at right angles to the motor shaft to drive a main drive pinion. Through suitable gearing this pinion drives at the required rate of speed the four shafts that are in turn each positively coupled to one of the four rolls of the machine. The drive mechanism is not described in further detail because it may be of any type known in the art to drive four output shafts from a single driving shaft with the desired input-output speed ratio.

Each of the four rolls that are mounted on the bed are adapted to be positively driven independently of the other. The relative positions of these rolls with respect to each other in the bending and straightening operations are shown in Figures 4 and 5 respectively. These rolls are indicated in these figures as A, B, C and D. The rolls A and B, as hereafter described, are journaled in fixed bearings in end frames on the bed. The roll C that is common to each of rolls A and B and forms a roll bite with each is journaled in the end frames but is so mounted that it may be bodily shifted with respect to them. The roll D is likewise shiftably mounted with respect to rolls A and B, and to this end is supported in links as hereafter described that are mounted for pivotal movement about the axis of the roll B.

The rolls A and B are driven from drive shafts 60 and 61 (Figure 3) in the housing through semi-rigid couplings. The roll C is driven from a driven shaft 65 through a universal coupling 67 to permit it to be rotated while it is in various selected positions with respect to the rolls A and B.

The roll D is bodily shiftable to permit its use in one position to supplement the rolls A, B and C to straighten a bent plate and in a second position to be idle while the other rolls only are used to bend a plate. This roll is driven by a universal drive coupling best shown in Figure 10 that comprises two universal joints 70 and 71, the one carried by the roll D and the other connected with an output shaft 72 extending from the housing 55. A coupling shaft 74 interconnects the two universal joints. Each universal joint receives a flattened tongue of the shaft 74 in modi-

fied ball and socket connections in couplings 70 and 71. In the latter coupling the tongue is held in place by a removable pin 80 to permit the coupling to be broken at will, and the drive to the roll D disconnected. To break the coupling 71 the pin 80 is first removed and the shaft 74 is lifted out of engagement with the drive shaft and supported in the dotted line position of Figure 10 by a block and tackle 85 slideably supported by pulley wheels on a guide rail 86. The guide rail 86 is swingably mounted on the housing 55 for movement in a plane generally parallel to the bed of the machine. By means of the swingably mounted block and tackle the free end of the shaft 74 may be moved and continue to be supported during the time the roll D is being moved to, and is in, the position shown in Figure 4.

In this position the three rolls A, B and C are employed for plate bending and the plate that is being bent passes through the rolls as indicated at P. This plate is fed into the roll bite formed by the rolls A and C until it comes in contact with the surface of the roll B moving in the direction indicated. The grip of rolls A and C on the plate and guiding action of the surface of the roll B feeds the plate into the bite between rolls B and C. As the plate passes out of the last named roll bite it will have been bent to a curved shape generally conforming to the path it has followed through the rolls.

To bend a plate P to a conical, as distinguished from a cylindrical, shape one end, preferably the inboard end, of the roll C may be moved upwardly away from the rolls A and B thereby to tilt the axis of this roll with respect to the axes of rolls A and B. The construction by which this is accomplished together with the manner in which a bent plate may be removed from the machine endwise of the rolls will be described hereafter in detail.

The rolls are shown schematically in Figure 5 in position to straighten a plate. In this figure the roll C has been moved up and positioned some distance away from the rolls A and B in a manner hereafter described. The roll D in its turn has been rocked with its links about the roll B to the position shown. At this time the coupling shown in Figure 11 for the roll D will be connected by securing the shaft 74 to the drive shaft 72 by the coupling 71 and the pin 80. When the rolls are in the position of Figure 5 they act in the manner of conventional straightening rolls and a bent plate fed through them will be straightened.

The rolls are mounted in cast end frames 90 and 91 formed as shown in Figures 1, 6 and 7 and bolted to the bed 30a. Each of the end frames is provided with a pair of bearings 94 and 95 including liners 97 to receive the journals of rolls A and B respectively. Each bearing is capped by a bearing cap 98 keyed to the end frames at 99 and secured in place by bolts 100. While the rolls A and B are so mounted that they are not bodily shiftable in the end frames the rolls C and D are each so mounted that they may be shifted bodily with respect to each other and to the other rolls in the machine.

The roll C is provided at each end with journals that are supported in vertically shiftable bearings so that one or both ends of the roll may be adjusted up or down with respect to the other rolls in the machine. The outboard bearing is so arranged that the roll housing may be removed from

the roll to permit a bent plate to be slipped endwise from between the rolls A, B and C.

The outboard journal of the roll C is rotatably received in a bearing sleeve 102 (Figure 6) in which is mounted a bearing liner 103. The exterior of this sleeve is provided with four bosses each having flat longitudinally tapered surfaces 104 that, as shown in Figure 7, make engagement with complementary tapered surfaces in a bearing block 105 that is mounted for pivoted movement in the plane of the axis of the roll so that it may be swung into and out of engagement therewith. The sleeve and block 105 are held together by a hand wheel 107 threaded in the block and carrying a pin 110 (Figure 7) adapted to engage within a bore provided for the purpose in the sleeve.

To restrain the roll against endwise movement a thrust bearing is provided by an annular shoulder at 115 formed by a flange on the outer end of the liner 103 and bearing against the end of the sleeve 102. A sliding bearing thrust ring is interposed between the shoulder 115 and a cap 117 bolted to the end of the roll shaft.

The entire outboard bearing assembly just described for the roll C is supported in the bearing block 105 that in turn is pivotally mounted in the end frame 90 to permit it to be rocked counterclockwise (Figure 7) and removed from the roll when it is desired to remove a bent plate endwise from between the three bending rolls. The shank of the block 105, indicated at 120 (Figure 6), is restrained against movement transversely of the axis of the roll C by bearing surfaces 121 in the end frame although it is free to rock in the plane of the roll axis as hereafter described. At its lower end the bearing block 105 terminates in a yoke with spaced arms 122 and 123. These arms are separated by an opening in which is received the flattened head 124 of a large screw 125 supported for vertical sliding movement in a sleeve bearing 127 in the end frame 90. The screw head 124 and the arms 122 and 123 of the block 105 are pivotally connected by a pin 130.

It will be seen that the outboard end of the top roll C may be shifted by raising or lowering the screw 125, the motion of which is transmitted through the pin 130 to the bearing block 105. To raise or lower the screw, threads indicated at 135 are provided on the shank and are engaged by a nut 138 that is freely rotatable in the housing 90 and restrained against movement along its axis by a thrust bearing 140 at one end and a shoulder 142 in the casting at the other end. A worm wheel 145 is bolted to the nut 138 and is driven by a worm 147 (Figure 6) mounted on a shaft 150 that extends generally parallel to the rolls and from one end frame to the other. Since the nut is restrained against axial movement and the screw 125 against rotative movement, the latter will be moved up or down as the shaft 150 is rotated. Lubrication for the parts just described is provided by an oil line 152 communicating at its inner end with a passage leading to the nut 138 and its associated parts, and at the other end provided with a removable cap of suitable form for the admission of lubricant. A normally plugged drainage hole 165 is provided for oil removal.

To permit vertical adjustment of the inboard end of roll C the mechanism for supporting and shifting the bearing block 105 up and down is duplicated in all its essential details in the inboard end frame 91 and hence is not further described or illustrated in the drawings. The shaft 150 carries a second worm similar to that indicated

at 147 to elevate and lower this inboard bearing. In general the two ends of the roll C will be elevated or lowered together to vary uniformly the spacing between this roll and the pair of rolls A and B. Under such conditions the entire shaft 150 is driven by a motor 157 (Figure 1) on the bed 30a to rotate the two worms 147 at the same speed.

In positioning the roll C to bend plates to a conical shape it is necessary to tilt it so that its axis is no longer parallel to the axes of the rolls A and B. This is accomplished by raising or lowering one of the bearings for roll C, preferably the inboard end, while the other is held stationary.

To accomplish this a clutch, indicated at 160 (Figure 1), is provided to disconnect the drive from the motor 157 to the outboard bearing. This clutch may be of the ordinary sliding key type that is well known in the art and shiftable by a hand lever to disconnect the outboard bearing drive when in one position and connect it when in the other. In the former position rotation of the motor 157 will raise or lower only the inboard bearing for the roll C and will leave the outboard bearing unmoved. In the latter clutch position both the inboard and outboard bearings for the roll will be moved in unison.

The outboard bearing block 105 is rocked counterclockwise (Figure 7) as indicated above and as illustrated in Figures 11 and 12 to remove it from the end of the roll when a plate is to be removed endwise. This is accomplished by withdrawal of the pin 110 through rotation of the hand wheel 107 to permit the bearing block to be swung away from the sleeve 102 by breaking contact therewith at the tapered surfaces 104. It will be seen that the outboard journal of the roll is at all times enclosed by sleeve 102 and cap plate 115 irrespective of the position of the bearing block. Thus the bearing is sealed against the ingress of dirt and also from blows that might destroy or damage it.

The mechanism by which the outboard bearing is shifted from a position of engagement (Figure 11) with the roll to a disengaged position (Figure 12) in which it is approximately horizontal is best illustrated in Figures 2 and 7. The shifting is accomplished through a lever 165, carried by a shaft 167 mounted in the end frame 90 for rocking movement about an axis parallel to the axis of the pin 130. This lever 165 is connected with the block 105 by a sliding roller connection such that it and the block may be rocked in the plane of Figure 7 about different centers in unison and at the same time remain connected together. To this end a roller 170 is provided on each side of the lever 165 to ride within a trackway 172 bolted to ears 173 and 174 that in turn are secured to the head and shank of the block 105. As the rollers 170 slide on the trackway they provide a shifting but positive pivotal connection between the lever 165 and the block 105. When the parts are in the position shown in Figure 12 the rollers 170 will be at the lower end of the track 172 and when the block 105 and the lever 165 have been rocked to substantially horizontal positions as shown in Figure 11 the relative position of the axes at 130 and 167 will cause the rollers to move in the trackways to a position adjacent the other end thereof.

To rock the lever 165 a worm gear (not shown) is mounted on the shaft 167 supporting the lever 165 and is engaged by a worm carried in a housing 175 and adapted to be rotated by a hand

wheel 471. To reduce the effort the operator is required to exert in turning the hand wheel a counter weight 180 (Figure 2) on a rocker arm suitably connected to the shaft 167 is provided to balance the weight of the block 105. The hand wheel is turned in the appropriate direction to rock the outboard bearing as desired and the lever 165 acting through rollers 170 effects the desired movement of the block 105.

When the outboard bearing is removed from the roll C the latter is supported at its inboard end by mechanism shown in Figures 1 and 9, so that the outboard end does not fall down onto rolls A and B. At its inner end roll C terminates in a sleeve 182 rigid therewith and extending a substantial distance from the inner end frame. Two tension rods 183 (Figure 9) are secured at one end to the bed 30a of the machine and connected at the other end by a cross frame member 184. A saddle 185, supported by a screw 192 in the cross frame member 184, is guided by the tension rods so that it may be moved up or down to bear against the inner end of the sleeve 182 in various adjusted positions of the roll and prevent it from rocking upwardly. This prevents the top roll from rocking downwardly (counterclockwise in Figure 1) about the inner end frame 91 when the outboard bearing is removed and dropping onto the outboard end of the lower rolls.

The saddle is adjusted up and down by means of the screw 192 with its head rotatably mounted in the saddle but restrained against axial movement therein. At its upper end the screw is threaded into a sleeve 193 secured in the cross frame 184 and also is slidably keyed at 194 to a worm gear 196 that may rotate in its housing but is restrained against movement therein along the line of the screw axis. The worm gear is engaged by a worm mounted on a shaft 198 terminating in a hand wheel 200. Rotation of the hand wheel causes rotation of the screw 192 and by reason of the threaded connection between the screw and the cross frame the saddle will be shifted up or down along the tension rods 183.

The power shaft 65 drives the roll C through the coupling member 67 lying partially within the sleeve 182 and connected to the roll and the drive shaft 65 respectively by universal joints to permit the roll to be driven in any adjusted position it may occupy in the end frames.

In addition to the three rolls that have already been described, the fourth roll D is provided. This roll is pivotally mounted on a pair of links, one at each end of the roll B. The mechanism by which this roll is mounted and adjusted in position is best shown in Figures 6 and 8 and will now be described in detail. Since this mechanism is the same at each end of the machine only that mechanism at the outboard end will be referred to. The roll B is provided at each end with a stepped journal comprising two portions of different diameters. The portion closest to the roll end is indicated at 210 and is mounted in bearings 95 in the end frame 90 as already described in connection with Figure 6.

The roll D is supported on the end frames by a pair of links 212 that are themselves pivotally mounted coincident with the axis of roll B on a journal 214 (Figure 8) of that roll B somewhat reduced in diameter from the journal 210. Each link 212 is roughly triangular in shape with bearings at each corner, one of which is a sliding bearing comprising a liner 215 secured in the link, and having at its outer end a cap 217 bolted to the

journal and forming with the liner a thrust bearing to prevent axial movement of the link on the roll. The outer end of each link is provided with a bearing 220 rotatably to receive the journal 222 of the roll D. The bearing includes a liner 223 secured to the link and forming a sliding bearing with the journal. At its outer end the journal is capped with plate 224 that engages an annular shoulder of the liner to form a thrust bearing therewith and prevent relative axial motion between the roll and the link.

To position the roll D in desired operating relation to the other rolls of the assembly it and its supporting links are rocked about the axis of the roll B. This rocking motion is applied by a screw 225 pivotally pinned to the link at 227 (Figure 6). The head 228 of the screw is flattened in the plane of Figure 6 to permit it to be inserted between parallel sides of the link 212 and thus be restrained against relative sidewise motion with respect to it. The lower end of the screw 225 is threaded at 229 and received within a correspondingly threaded nut 230 that is mounted for rotation only in a casting 232 carried by the end frame 90 and capped at the bottom by a plate 234 in such manner that the two parts cooperate to prevent the nut 230 from shifting bodily within them. The casting 232 is provided with a pair of trunnions 235 (Figure 8) that are pivotally mounted in extensions 240 and 241 of the frame 90 to permit the nut 230 to be rocked in the end frames to prevent binding between the cooperating threads as the bolt is inclined when the link is shifted.

To raise and lower the link 212 an external worm gear is formed on the nut 230 and is engaged by a worm carried on a shaft 245 that extends parallel to the axes of the rolls. As this shaft is rotated by a motor 250 (Figure 1) the shaft 245 rotates the nut which acts through the parts described to shift the roll D with respect to the other rolls.

The link mechanism just described for supporting and moving the roll D is, as previously indicated, duplicated at the inboard bearing end of the machine. Here the counter part of the casting 232 is shown at 232a and the counter part of the bolt 225 is shown at 225a. The two links are raised and lowered in unison, thus at all times maintaining the axis of the roll D parallel with the axes of the rolls A and B.

The mechanisms for bodily shifting rolls C and D with respect to the rolls A and B in the machine is, as described above, power driven. It is preferable to provide for these mechanisms safety means to prevent the rolls from being shifted in the frames so far that they reach the end of their intended limit of travel with resultant damage to the machine because the motors 157 or 250 do not stop.

To eliminate this possibility with motor 157 limit switches 255 are shown as they are applied to the adjustment for the roll C in Figures 1 and 7. These switches each include and are actuated by a pivoted arm 257 (Figure 7) to cut off the driving motor when either end of the arm is rocked toward the switch box 258. A roller 260 is mounted on the screw 125 and by virtue of cam surfaces 261 at each end of the arm 257 will rock that arm inwardly at either end of a line of travel equivalent to the distance between cam surfaces. By means of conventional wiring (not shown) the current supply to the motor 157 is cut off automatically whenever the intended limit of travel is reached by the screw 125. This mecha-

nism is duplicated at each end frame as shown in Figure 1 to control the motion of each of the bearings for the roll C.

Although this mechanism has been shown and described in connection with the roll C identical mechanisms may be used to control the motion of the links 212 and hence the roll D. This may be accomplished by securing to the screw 225 a roller such as 260 and to a convenient part of the casting 232 a switch mechanism such as 255 and wiring the latter to control the current supply to the motor 250.

The machine just described may be set up readily either to bend or straighten metal plates of varied thickness by adjustment of the rolls C and D with respect to rolls A and B. In like manner the machine may be set up to impart a definite shape to a plate by controlling the radius to which it is bent or the amount it is straightened. In general the radius to which the plate is bent is determined by the position of the top roll C with respect to the rolls A and B and this roll position may be altered by adjustment of the screws 125 in each of the end frames. The sheet may be formed to either a cylindrical or conical form depending upon whether or not the roll C is set to be parallel to the rolls A and B.

After a plate has been bent as described above it frequently will have such a shape that there is insufficient spacing between the two opposed plate edges to permit removal except endwise of the rolls. In this case the bearing block 105 is rocked out of engagement with the roll C to the horizontal position shown in Figure 12 and the saddle 185 adjusted to prevent the outboard end of the roll C from dropping down. The plate may then be removed endwise of the rolls to the left as shown in Figure 1.

To position the rolls for straightening a plate the screws 125 and 225 are adjusted until the general position of the rolls as shown in Figure 5 is attained, the exact position being determined by the degree of straightening necessary and the thickness of the plate.

Plates to be shaped in the machine are preferably passed through the rolls in such a direction that they travel from left to right in Figures 4 and 5 and first enter the bite between rolls A and C.

Various changes and modifications in my invention will be apparent to those skilled in the art. Therefore, it is to be understood that my patent is not limited to the preferred forms described herein or in any manner other than by the scope of the appended claims.

I claim:

1. In a roll bending and straightening machine, a base with two spaced end frames thereon, a pair of rolls mounted for rotation in said end frames, a third roll rotatably carried by said end frames and bodily shiftable with respect to said end frames, a pair of links pivotally carried by said end frames on the axis of one of the rolls of said pair, a fourth roll rotatably carried in said links, means to shift said links and position said fourth roll with respect to said third roll, power mechanism to drive said fourth roll and a universal connection between said fourth roll and said power mechanism.

2. In a roll bending and straightening machine, a base with two spaced end frames thereon, a pair of rolls mounted for rotation in said end frames, a third roll rotatably carried by said end frames and bodily shiftable with respect to said end frames, a pair of links pivotally carried by

said end frames on the axis of one of the rolls of said pair, a fourth roll rotatably carried in said links, power driven screws engaging each of said links intermediate its pivot and the axis of

5 said fourth roll to shift said links and position said fourth roll with respect to said third roll, power means to drive said screws simultaneously, power mechanism to drive said fourth roll and a universal drive connection between said fourth roll and said power mechanism.

3. In a machine of the class described, a base including two spaced end frames, at least one roll rotatably supported by said end frames, two links, one carried by each end frame on an axis 15 substantially coinciding with the axis of said rotatably supported roll, aligned roll bearings in said links, a second roll carried in said bearings to cooperate with said first roll, second links pivotally carried by said first links, means positively engaging said second links to shift the same, and roll drive mechanism to rotate said rolls.

4. In a machine of the class described, a base including two spaced end frames, at least one roll rotatably supported by said end frames, two links, one carried by each end frame on an axis 25 substantially coinciding with the axis of said rotatably supported roll, aligned roll bearings in said links, a second roll carried in said bearings 30 to cooperate with said first roll, second links pivotally carried by said first links intermediate said axes and said bearings and including a screw threaded portion, nut members pivotally carried by said base and engaging said threaded portions, power means to rotate said nuts and by shifting said threaded portion and thereby moving said links to position said second roll with respect to said one roll and roll drive mechanism to drive said second roll.

40 5. In a machine of the class described, a base including two spaced end frames, at least one roll rotatably supported by said end frames, two links, one carried by each end frame on an axis substantially coinciding with the axis of said

45 rotatably supported roll, aligned roll bearings in said links, a second roll carried in said bearings to cooperate with said first roll, second links pivotally carried by said first links intermediate said axes and said bearings and including a screw threaded portion, nut members pivotally carried by said base and engaging said threaded portions, power means to rotate said nuts and by shifting said threaded portion and thereby moving said links to position said second roll with respect to said one roll and roll drive mechanism to drive said second roll.

50 6. In a machine of the class described, a base including two spaced end frames, at least one roll rotatably supported by said end frames, two links, one carried by each end frame on an axis substantially coinciding with the axis of said rotatably supported roll, aligned roll bearings in said links, a second roll carried in said bearings to cooperate with said first roll, second links pivotally carried by said first links intermediate said axes and said bearings and including a screw threaded portion, nut members pivotally carried by said base and engaging said threaded portions, power means to rotate said nuts and by shifting said threaded portion and thereby moving said links to position said second roll with respect to said one roll, roll drive mechanism terminating in a shaft in substantial alignment with said second roll and journaled in fixed bearings supported by said base, and a drive connection between said mechanism and said second roll.

60 7. In a roll bending machine, a base with two spaced end frames thereon, a pair of bending rolls rotatably mounted in said end frames with their axes in a substantially horizontal plane, a third roll rotatably mounted in said end frames parallel to said pair of rolls, roll drive mechanism positively connected to said third roll adjacent one of said end frames, a pair of links pivotally carried by said end frames on the axis of one of the rolls of said pair, a fourth roll rotatably carried in said links, means to position said fourth roll in sheet shaping relation with said third roll, and a universal connection to

70 drive said fourth roll positively from said roll 75

drive mechanism in predetermined relation with said third roll.

7. In a roll bending machine, a base with two spaced end frames thereon, a pair of bending rolls rotatably mounted in said end frames with their axes in a substantially horizontal plane, a third roll rotatably mounted in said end frames parallel to said pair of rolls, a removable bearing pivotally mounted in the outboard end frame to support said third roll, a sleeve integral with said third roll, aligned therewith, and extending on the opposite side of said inboard frame from said outboard frame, a framework supported from said base and overlying the end of said sleeve, means carried by said framework and movable to a position to support said third roll on removal of said removable bearing and roll drive mechanism including a coupling partially housed in said sleeve positively connected to said third roll adjacent the inboard end frame.

8. In a roll bending and straightening machine, a base with two spaced end frames thereon, a pair of bending rolls rotatably mounted in said end frames with their axes in a substantially horizontal plane, a third roll rotatably mounted in said end frames parallel to said pair of rolls, a removable bearing pivotally mounted in the outboard end frame to support said third roll, a sleeve integral with said third roll, aligned therewith, and extending on the opposite side of said inboard frame from said outboard frame, a framework supported from said base and overlying the end of said sleeve, means carried by said framework and movable to a position to support said third roll on removal of said removable bearing, roll drive mechanism including a coupling partially housed in said sleeve positively connected to said third roll adjacent the inboard end frame, a pair of links pivotally carried by said end frames, a fourth roll rotatably carried in said links, means to position said fourth roll in sheet shaping relation with said third roll, and a universal connection to drive said fourth roll positively from said roll drive mechanism in predetermined relation with said third roll.

9. In a sheet forming machine including a plurality of cooperating rolls mounted in spaced end frames, a construction for one of said end frames comprising an upright casting with a ver-

tical slideway therein, a roll bearing block slidably guided in said slideway, mechanism including a pivoted connection to retain said bearing block in position in said frame or permit the same to be swung out of said slideway to separate the bearing block and the roll, a lever pivoted at one end in the end frame on an axis parallel to the bearing block axis and at the other end connected to said bearing block and means to rock said lever about its pivot and thereby swing said bearing block into and out of said slideway.

10. In a sheet forming machine including a plurality of cooperating rolls mounted in spaced end frames, a construction for one of said end frames comprising an upright casting with a vertical slideway therein, a roll bearing block slidably guided in said slideway, a member adapted for movement parallel to said slideway in said one end frame, a pivotal connection between said bearing block and said member to permit said block to be swung about an axis out of said slideway to separate the bearing block and the roll, a lever pivoted at one end in the end frame on an axis parallel to the bearing block axis and at the other end connected to said bearing block and means to rock said lever about its pivot and thereby swing said bearing block into and out of said slideway.

WILLIAM RODDER.
